DESIGN FOR A COMBINED LAMP AND STAND FOR A DIAL TELEPHONE

William C. Swalley and Arthur J. Lichtinger,
Cleveland, Ohio, assignor to The Dialite Company, Cleveland, Ohio, a corporation of Ohio

Application February 17, 1939, Serial No. 83,068

Term of patent 7 years

To all whom it may concern:

Be it known that we, William C. Swalley and Arthur J. Lichtinger, citizens of the United States, residing respectively, at Cleveland, in the county of Cuyahoga and State of Ohio, and Cleveland, in the county of Cuyahoga and State of Ohio, have invented a new, original, and ornamental Design for a Combined Lamp and Stand for Dial Telephone, of which the following is a specification, reference being had to the accompanying drawing, forming a part thereof, in which:

Fig. 1 is a perspective view of our combined lamp and stand for a dial telephone;

Fig. 2 is a top plan view of the combined lamp and stand; and

Fig. 3 is a side elevation of the stand.

We claim:

The ornamental design for a combined lamp and stand for a dial telephone, substantially as shown.

WILLIAM C. SWALLEY.
ARTHUR J. LICHTINGER.
